(57) **CLAIM**

The ornamental design for a vehicle decoration, as shown and described.

DESCRIPTION

FIG. 1 is a perspective view of a vehicle decoration showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a vehicle decoration as in FIG. 1 showing my new design in use on a vehicle.

In the drawings, the broken lines showing a vehicle illustrate environment and form no part of the claimed design.
